UNITED STATES PATENT OFFICE.

HARRY E. BEARD, OF READING, PENNSYLVANIA, ASSIGNOR TO THE NOLDE AND HORST COMPANY, OF READING, PENNSYLVANIA, A CORPORATION OF PENNSYLVANIA.

CIRCULAR-KNITTING MACHINE.

Application filed Septcmber 13, 1924. Serial No. 737,480.

My invention relates to circular knitting machines adapted to continuously knit two yarns into the body of a fabric; and my object is to provide for automatically positioning these continuously knitted-in yarns so that one or the other will appear upon the surface in certain portions of successive courses as required for the production of vertical stripes without floating of either 10 yarn.

To this end my invention provides for modifying the form of certain of the sinkers and needles commonly employed in such machines so as to cause in determined wales 15 a reversal of the normal positions of the regularly fed yarns during the drawing of the latter through previously formed loops; thereby displaying different yarn in such wales from that displayed by the normal 20 action of the unmodified elements with resulting stripe-effects; as fully set forth in connection with the accompanying drawings and clearly defined in the subjoined claims.

Fig. 1 is a partial sectional elevation showing part of a known knitting machine, with an ordinary sinker and knitting needle indicated on one side and my special sinker and cooperating needle on the other; the section being on the line 1—1 of Fig. 2.

Fig. 2 is a diagrammatic plan view indicating the circles of needles and sinkers, with the special sinkers shown in heavier lines and the cooperating needles set out of normal circular alinement.

Figs. 3 and 4 illustrate respectively an ordinary sinker and a special sinker; and Figs. 5 and 6 illustrate respectively an ordinary needle and one that is specially set in to cooperate with a special sinker.

Fig. 7 is a diagrammatic view indicating the run of the yarns to the needles; and Figs. 8, 9, 10 diagrammatically indicate the positioning of the two threads during normal knitting, while Figs. 11, 12, 13 diagrammatically indicate the reversed relation thereof which is automatically effected by the special sinkers and cooperating needles.

Fig. 14 is an enlarged fabric view indicating different exposed yarns in the normally knitted and specially knitted wales.

All the needles, a , a' , are vertically moved as usual in the needle cylinder A by cams in ring B, to form the knitting wave indicated; and all the sinkers are also moved in radial

lines between the needles as usual; while the two yarns c and d are continuously fed through their respective guide fingers e and f to continuously knit them jointly into a double-yarn fabric.

Both the ordinary form of sheet-metal sinkers indicated in Fig. 3, and my special form 11 shown in Fig. 4, may have the usual contour so far as the lower guiding and cam-engaging portions are concerned; but the contour of the upper yarn-supporting portions is essentially different. The thread supporting edge 10^a of the ordinary sinker 10 is substantially a straight horizontal line, and the threads supported upon it are delivered into a receiving notch 10^b formed by an overhang 10^c; whereas in the special form of sinker 11 the thread-supporting edge is curved so as to form a humped portion 11^a and a downwardly and outwardly inclined receiving notch 11^b, whereby the relative positions of the needle-lowered yarns is reversed as compared with the knitting effected on the ordinary sinkers 10. The needles a and a' differ only in that the special ones a' have their hooked ends set inward from the normal needle circle so as to properly cooperate with the special sinkers 11 in reversing the positions of yarns.

The action upon the two threads, of the ordinary sinkers and needles shown in Figs. 3 and 5 respectively, is illustrated in the diagrammatic views Figs. 8, 9, and 10 as uniformly positioning the darker colored of the two threads on the outer surface of the fabric, as in fact occurs; Fig. 8 indicating the relative positions of the two threads in the hook of a raised needle; Fig. 9 their retained position in the thread receiving notch 10^b of the advanced sinker 10, and on the hook of the lowered needle a as it is about to be drawn through a previously formed loop indicated; and Fig. 10 indicating the later retained relation of the yarns whereby said (dark) thread is uniformly presented upon the outer surface of the fabric during such ordinary knitting.

The main object of my invention, as stated, is to provide for reversing this normal relation of the threads in determined wales, so as to there present the other (lighter) thread on the outer surface and thus produce desired stripe effects; and to accomplish this without interference with

the usual continuous operation of the machine. This I have accomplished by simply changing the yarn-contacting contour of determined sinkers as described and co-operatively varying the positions of the hooks of adjacent needles, as indicated respectively in Figs. 4 and 6; and the diagrammatic views Figs. 11, 12, 13 show the apparent action upon the yarns in effecting 10 such actual reversal of their positions in corresponding wales of the fabric structure. The described changes in the usual sinker contour whereby a positive downward and outward slant is given to the yarn-receiving notch 11^b, and a curved yarn-contacting hump 11^a at the mouth of this downwardly slanted notch, provides an arcuate supporting edge leading into the latter which exerts a position-reversing action upon the two 15 yarns brought into contact therewith by the lowering of the needle; this reversing action being assisted and insured by giving an inward set to the hook end of the needle as indicated in Fig. 6, whereby the upper 20 (dark) thread is initially deflected inwardly as indicated in Fig. 11. As the needle descends and the sinker is moved inward as usual, the lower (light) thread in the needle is caused to ride upon the curved hump 11^a 25 of the special sinker, into the downwardly slanted notch 11^b thereof, so that the upper (dark) thread will be positioned inward of the fabric instead of outward, and with the effect of showing a different thread in 30 the wales having such special sinkers and needles and thus producing corresponding longitudinal stripes.

It will be seen that my invention thus provides in a very simple manner for automatically producing vertical stripe effects 40 by determinedly reversing the relative positions of the two continuously knitted-in threads, without floating either of the latter.

45 While the different thread-supporting con-

tour of the special sinkers is adapted to exert the desired position-reversing action upon the two yarns as stated, so as to produce a stripe effect, it will be understood that the specially set cooperating needles 50 serve to insure such complete and uniform reversing of the yarn positions as is required to produce a high class product.

What I claim:—

1. A circular knitting machine comprising 55 a series of vertically reciprocated needles, a circular series of radially reciprocated sinkers, and means for continuously feeding two yarns to all of said needles; one set of said sinkers having a thread-supporting 60 contour adapted to position the yarns seated thereon by their corresponding needles in one determined knitting relation, and another set of said sinkers having a different thread-supporting contour whereby the 65 yarns seated thereon by their corresponding needles will be reversely positioned relatively; the needles corresponding with said second set of sinkers having their hooked 70 ends out of circular alinement with the other needles.

2. In a circular knitting machine comprising 75 a number of yarn-feeds and a circular series of vertically reciprocated needles continuously operative upon two yarns; a circular series of radially reciprocated sinkers comprising two sets of differing contour, each sinker of one set having a substantially horizontal yarn-supporting edge and receiving notch, while each sinker of the second set has a humped yarn-supporting edge 80 with a downwardly and outwardly inclined receiving notch, and the needles corresponding with said second set of sinkers having their hook-end portions out of circular 85 alinement with the other needles; whereby the two yarns are reversely positioned in the knitted web.

In testimony whereof I affix my signature
HARRY E. BEARD.
